UNITED STATES PATENT OFFICE.

TRACY L. PAINE, OF MILWAUKEE, WISCONSIN.

HANDLE FOR DIAL-LOCK KNOBS.

SPECIFICATION forming part of Letters Patent No. 295,582, dated March 25, 1884.

Application filed July 26, 1883. (No model.)

To all whom it may concern:

Be it known that I, TRACY L. PAINE, of Milwaukee, in the county of Milwaukee, and in the State of Wisconsin, have invented certain new and useful Improvements in Knobs or Handles for Combination-Locks; and I do hereby declare that the following is a full, clear, and exact description thereof.

My invention relates particularly to safe locks; and it consists in a detachable handle for manipulating the knobs of the combination-dials, as will be more fully described hereinafter.

In the drawings, Figure 1 is a perspective view of that portion of a safe-door that contains the combination-dial with my device attached to the knob thereof. Fig. 2 is a longitudinal section of my detachable handle. Fig. 3 is a cross-section of the same on the line $x-x$ of Fig. 2, and Fig. 4 is a front elevation of the parts shown in Fig. 1.

A is the dial-plate that carries the numbers, and B is the knob. C is my detachable handle, the inner end of which terminates in a claw-shaped flange, C', and near this flange the upper side of the handle is grooved, as shown at $c-c$, Fig. 3, to take a sliding plate, D, one end of which terminates in a claw-shaped flange, D', and the other in a screw-bolt, d, which latter passes through the flange C' at its base to receive a set-nut, E. The flanges C' and D' are preferably serrated or corrugated on their concaved sides, that they may take hold the more readily when they are clamped over a knob.

It will be observed that my device may be attached to knobs of any size, and when in position securely clamped on the said knob by means of the set-nut E, already described.

It has been found by experience that much time is lost (especially on cold mornings, by 40 reason of the numbness of the fingers) in endeavoring to turn the knob of the safe-lock to a particular combination of the dial-plate, and also frequently from nervousness, when there is especial need for haste, or when the operator's 45 hand is, from any cause, unsteady. With my device all this is obviated, and the knob may be turned readily, quickly, and with the greatest accuracy, thereby effecting a great saving of time and temper. 50

In safes newly constructed my handle may be cast solidly with the knob, as a part or extension thereof; but the detachable form herein illustrated is preferred, so as to adapt it for use with the innumerable number of safes now 55 constructed and in use all over the country.

Having thus described my invention, what I claim as new, and desire to secure by Letters Patent, is—

A detachable handle for adjustment to safe 60 dial-plate knobs, consisting of two parts, one sliding upon the other, and having claw-shaped flanges curving outwardly and then inwardly, and provided with serrations or corrugations upon their concaved surfaces, to firmly grasp 65 the knob between them, together with a screw-bolt and set-nut, to rigidly fasten the flanges against the knob, substantially as set forth.

In testimony that I claim the foregoing I have hereunto set my hand, on this 21st day of 70 May, 1883, in the presence of two witnesses.

TRACY L. PAINE.
